Patented Feb. 15, 1966

203,789

HYDROTHERAPY BATH UNIT

Samuel L. McNair, 1200 S. Highland,
Fullerton, Calif.

Filed Mar. 8, 1965, Ser. No. 84,136

Term of patent 14 years

(Cl. D83—1)

Fig. 1.

Fig. 2.

Fig. 3.

Fig. 4.

Fig. 5.

FIG. 1 is a perspective view of a hydrotherapy bath unit embodying my new design;

FIG. 2 is a side elevational view of same taken from the side opposite that seen in FIG. 1;

FIG. 3 is an end elevational view of same taken from the left hand end of FIG. 2;

FIG. 4 is an end elevational view of same taken from the right hand end of FIG. 2; and

FIG. 5 is a bottom plan view of same.

I claim:

The ornamental design for a hydrotherapy bath unit, as shown and described.
